UNITED STATES PATENT OFFICE

JOHN L. MCKAY, OF MINNEAPOLIS, MINNESOTA

RESCUE APPLIANCE FOR SUBMARINES

Application filed February 11, 1928. Serial No. 253,668.

My present invention relates to a rescue appliance for submarines and has for its primary object to provide a submarine with a fresh air supply hose to which is attached a buoy or other lifting device arranged to be released by a control from within the submarine, in case of an accident in which the submarine is sunk or cannot rise when maneuvering under water, to carry the connected end of the hose to the surface of the water. This lifting device, after carrying the connected end of the hose to the surface of the water, floats thereon and acts as a signal from the submarine so that searchers may easily locate the same.

The appliance also includes the necessary apparatus for drawing a supply of fresh air through the hose to the submarine. To further assist the searchers in locating the submarine, the lifting device is provided with a signal, either audible or visual, or both, together with an antenna for use in broadcasting or in receiving messages. The appliance further includes a cage operable from either end of the hose for carrying messages, food or drink.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view showing a submarine in diagram resting on the bed of a body of water and with the rescue appliance released;

Fig. 2 is a view in transverse vertical section of the appliance and a portion of the submarine, certain parts of said appliance being indicated in different positions by means of broken lines;

Fig. 3 is a view principally in central vertical section showing the upper end portion of the fresh air supply pipe before the cap is removed;

Fig. 4 is a side elevation of the upper end portion of the air supply pipe with the cap removed;

Fig. 5 is a fragmentary detail view prin-

cipally in section showing the cage within the air supply hose;

Fig. 6 is a transverse section of the hose; and

Fig. 7 is a view of the cage in transverse section with the door thereof indicated in an open position by means of broken lines.

The numeral 10 indicates as an entirety a submarine resting on the bed of a body of water *z* with the exception of its deck 11 and one of its bottom plates 12. Extending from the bottom plate 12 to the deck 11 is a closed housing 13 having a lower or water-tight compartment 14, an intermediate or hose compartment 15 and an upper or buoy compartment 16. Said water-tight compartment 14 is provided with a manhole 17 normally closed by a heavy screw-operated cover plate 18.

Below the manhole 17 is a water-tight window 19 closed by a heavy piece of glass through which the interior of the compartment 14 may be viewed. An air suction pump 20, the intake of which leads from the compartment 14 is arranged to discharge into the submarine compartment in which the housing 13 is located. It is, of course, understood that this suction pump 20 may be connected to fresh air distributing pipes, not shown, leading to any part or parts of the submarine. A water pump 21, the intake of which leads from the compartment 14 is arranged to discharge through the bottom plate 12.

A buoy 22 is held within the compartment 16 and rests on a seat 23 in the bottom of said compartment and which seat comprises a plurality of narrow circumferentially spaced webs. The diameter of the buoy 22 is such as to permit a free passage of the water there-around, through the seat 23 and into the hose compartment 15 for floating the buoy 22, as will hereinafter appear. The compartment 16 has an open upper end in registration with a hatchway 24 in the deck 11, normally closed by a sliding gate 25 which forms a water-tight joint with said deck to prevent water from entering the compartments 15 and 16. This gate 25, as shown, is operated by a screw 26 arranged to be propelled by an electric motor 27.

Coiled within the compartment 15 is a hose 28, the lower end of which extends through the bottom of said compartment and into the air-tight compartment 14. The upper end of the hose 28 is attached to the lower end of a fresh air supply pipe 29 which forms a continuation of said hose and extends axially through the buoy 22 and above the top thereof. This hose 28 will be so constructed as to withstand a predetermined water pressure and not collapse under the action thereof. Leading from the bottom of the compartment 15 is a valve-equipped drain 30.

The upper end of the air pipe 29 is normally closed by a cap 31 and below this cap said pipe is provided with a plurality of circumferentially extended slots or air intake passages 32. A long displaceable cap 33 is telescoped over the upper end of the air pipe 29, has screw-threaded engagement therewith and encloses the air passages 32. Secured to and projecting above the buoy 22 is a tripod 34 on which is supported an antenna 35 and above said antenna a flashlight 36.

In case of accident to the submarine, when maneuvering under water, that would prevent the same from rising or in case of accident in which the submarine is sunk, the crew may start the motor 27 and operate the gate 25 to open the hatchway 24 and flood the compartments 15 and 16. This flooding of the compartments 15 and 16 will produce sufficient pressure on the bottom of the buoy 22 which is only covered by the seat 23 to lift said buoy from its compartment 16, through the hatchway 24 and into the body of water where the same will rise to the surface thereof and float, as shown by full lines in Fig. 1 and broken lines in Fig. 2. During the lifting of the buoy 22 it carries with it the connected end of the hose 28 which is uncoiled from its compartment 15 and drawn upward through the seat 23, compartment 16 and hatchway 24.

The wire cables 37 for the antenna 35 and flash light 36 are embedded in the walls of the hose 28 and extended to the necessary operating apparatus within the submarine. Obviously, the antenna permits the crew to send messages or receive the same and the floating buoy 22 and flash light 36 or other signal which may be substituted therefor act as a signal from the submarine to assist the searchers in readily locating the same.

The searchers, upon locating the buoy, will immediately remove the cap 33 so that the air pump 20 may be started to furnish a supply of fresh air to the crew. In case of any leakage into the compartment 14, which may be determined by looking through the window 19, the pump 21 may be operated to remove the water from said compartment. In place of the cap 33 other means may be used for closing the air passages 32 while the hose 28 is being lifted to the surface of the water and re-

moved by means under the control of the crew in the submarine so that they do not have to wait until the rescue party arrive before securing a fresh supply of air.

To permit messages to be carried back and forth between the rescue party and the crew in the submarine, as well as conveying food and drink to said crew, there is provided a cage 38 of cylindrical form and of such diameter that it may be readily drawn through the hose 28 without cutting off the entire air passage therethrough. This cage 38 is provided with reversely extended flexible connections 39 and 40, the former of which extends through the hose 28, is attached to the cap 31 and holds the cage 38 suspended within the compartment 14 just below the discharge end of the hose 30. The connection 40 is normally wound on a windlass drum within the compartment 14 and indicated as an entirety by the numeral 41. Any suitable means may be provided for operating this windlass drum 41 outside of said compartment. The rescue party, by removing the cap 31 may draw the connection 39 upward through the hose 28 and thereby lift the cage 38 to the surface of the water. During this lifting of the cage 38, the connection 40 is unwound from the windlass drum 41. The crew may return the cage 38 to the compartment 14 by operating the windlass drum 41 to wind the connection 40 thereon.

The cage 38 is provided with a hinged door 42 normally held closed by a collar 43 on the cage 38 held in an operative position by a bayonet joint 44. Within the cage 38 is a removable cover-equipped box or carton 45 for holding, for instance, written messages.

What I claim is:

1. In a submarine, the combination with an air supply hose, one end of which is secured to the submarine, of a buoy on the submarine attached to the other end of said hose and arranged to be released into the water for lifting the attached end of the hose to the surface thereof, a cage in the hose, and connections for driving the cage through the hose from either end thereof.

2. The combination with a submarine having a buoy compartment, a hatchway leading to said compartment, a gate normally closing the hatchway with a water-tight joint, a hose compartment into which the buoy compartment opens, of a buoy in the buoy compartment, and an air supply hose in the hose compartment and having one of its ends anchored in respect to its compartment, the other end of the hose being attached to the buoy, said gate when opened being arranged to cause the flooding of said two compartments to lift the buoy from its compartment through the hatchway and release the same to carry the connected end of the hose to the surface of the water, a water-tight compartment into which the lower end of the hose is ar-

5 ranged to discharge, a cage in said water-tight compartment and having reversely extended connections, one of which extends through the hose to the buoy by which the cage may be lifted in the hose, and the other of said connections affording means whereby the cage may be returned to said water-tight compartment, and a normally closed man-hole leading to said water-tight compartment.

10 3. In a submarine, the combination with an air supply hose, one end of which is secured to the submarine, of a buoy on the submarine attached to the other end of said hose and arranged to be released into the water for lifting the attached end of the hose to the surface thereof, a cage normally at the inner end of the hose and positioned to be drawn therethrough, and a pair of reversely extended

15 20 cables attached to the buoy, one of said cables being extended through the hose whereby the cage may be lifted therein to the buoy, the other of said cables being arranged to be laid in the hose by the cage during its lifting

25 movement therein whereby the same may be used to return the cage.

4. In a submarine the combination with a hose one end of which is secured to the submarine, of a buoy on the submarine attached to the other end of the hose and arranged to be released into the water for lifting the attached end of the hose to the surface thereof, and a cage attached to be moved through the hose.

35 In testimony whereof I affix my signature.
JOHN L. McKAY.
